CASING FOR A MARKING PEN

Robert Hankins, 3455 Bertha Drive, Baldwin, N.Y.

Filed Jan. 28, 1963, Ser. No. 73,327

Term of patent 14 years

(Cl. D74—17)

Fig. 1.

Fig. 2.

Fig. 3.

Fig. 4.

Fig. 5.

FIG. 1 is a side elevational view of a casing for a marking pen, showing my new design;

FIG. 2 is a front elevational view thereof;

FIG. 3 is an enlarged top plan view;

FIG. 4 is an enlarged bottom plan view; and

FIG. 5 is an enlarged sectional view taken along the line 5—5 of FIG. 1 in the direction of the arrows.

I claim:

The ornamental design for a casing for a marking pen, as shown.
